United States Patent Office.

CLARK S. SANFORD, OF LENA, ILLINOIS.

Letters Patent No. 99,243, dated January 25, 1870.

IMPROVEMENT IN NECK-YOKES.

The Schedule referred to in these Letters Patent and making part of the same.

To all whom it may concern:

Be it known that I, CLARK S. SANFORD, of Lena, in the county of Stephenson, and State of Illinois, have invented a new and useful Improvement in Neck-Yokes; and I do hereby declare that the following is a full and exact description of the same, reference being had to the accompanying drawings, and to the letters of reference, marked thereon.

This invention relates to that class of neck-yokes in which rack-bars are used in connection with a pinion, for the purpose of permitting the lateral adjustment of the end-rings, without moving the pole; and consists in the general combination and arrangement of the various parts.

The details of construction and manner of operation will be fully described hereinafter.

In the drawings—

Figure 1 is a plan view of my invention inverted;

Figure 2 a similar view of one of the racks; and

Figures 3 and 4, sectional views, through lines *x x* and *y y*, fig. 1.

To enable others skilled in the art to make and use my invention, I will now proceed to describe its construction and operation.

A represents the neck-yoke proper, which is constructed of any suitable form and size.

B represent rack-bars, which are constructed with teeth *b*, flanges *b¹*, arms *b²*, and slides *b³*. These bars are located in suitable sockets in the lower side of the neck-yoke, and have room for lateral movement.

C represents a pinion, which is also provided with a flange, *c*. Instead of passing the centre-bolt through the pinion, as is usual, the latter is pivoted in any suitable manner, and the bolts pass through the yoke upon each side, as shown.

d d represent plates located at each end of the yoke, the edges of which project over the groove *a*, and form ways upon which move the slides *b³* of the rack-bars,

the latter being provided with flanges, as shown, above and below the edges of the plates, so that displacement is rendered impossible.

The outer ends of the arms *b²* are either provided with small rings to receive the large rings for the breast-chains, or with a staple to receive the pole-straps.

E represents a covering-plate, by means of which the internal parts are protected.

The operation of my yoke is similar to others of this class. The end-rings may be adjusted laterally when desired, by the simple movement of the animal.

The advantages of the special construction shown, are as follows:

First, by providing the rack-bars and the pinion with flanges, their strength is so much increased that much smaller sizes can be used, and hence, they may be employed with buggies and light carriages, where heretofore the excessive size and weight of this class of yokes has rendered them wholly unfit for such use.

Second, by providing the rack-bars with arms and slides, as shown, the bearing-surface is much reduced, and, consequently, the friction is also.

Third, by the combination and arrangement of the various parts, a light yoke is produced which at the same time possesses great strength.

Having thus fully described my invention,

What I claim as new, and desire to secure by Letters Patent, is—

The neck-yoke described, consisting of the yoke *A*, flanged bars *B*, pinion *C*, and ways *d*, the whole being combined and arranged as and for the purpose described.

This specification signed and witnessed, this day of , 186

CLARK S. SANFORD.
